[57]

ABSTRACT

A nest plate assembly for an apparatus for forming fabric blanks comprising a nest plate having two end portions and a removable intermediate portion which may be made in various lengths for forming blanks of various sizes. The nest plate is supported by a carriage assembly including two separate supporting structures holding the end portions of the nest plate, and means are provided for moving the supporting structures for sliding the two end portions of the nest plate towards or away from each other for positioning a predetermined intermediate portion of the nest plate between the end portions thereof. The nest plate has a cavity shaped in accordance with the finished blank and a punch assembly is provided for inserting a somewhat larger blank into the cavity of the nest plate. The punch assembly comprises four punch sections overlapping each other and arranged to form a four corner punch assembly. A head structure is provided for supporting the punch assembly and includes two separate plates slidably mounted towards or away from each other. To each one of such plates are attached two punch sections for permitting adjustment of the length of the punch assembly to suit the length of the nest plate assembly. Screw means are secured to the head structure and connected to the plates for easily adjusting the length of the punch assembly.

APPARATUS FOR FORMING FABRIC BLANKS

This is a division of U.S. Pat. application Ser. No. 841,884, filed July 15, 1969.

This invention relates to an apparatus for forming fabric blanks such as, for example, collar bands.

Such machines usually comprise a nest plate having an opening therein shaped in accordance with the shape of the finished blanks and over which a blank somewhat larger than the opening is positioned. A collapsible punch assembly is adapted to be inserted into the opening of the nest plate to force the blank through the opening against a pressure plate thereby causing the bordering portion of the blank to bend at right angles to the body thereof because of its engagement with the edges of the opening. The machine further comprises infolders for folding the bordering portion of the blank over the top edge of the punch assembly. A mechanism is also provided for collapsing the punch assembly for withdrawing the same from underneath the bordering portion of the blank. Finally, the pressure plate positioned in the above-mentioned opening is moved upwardly to press the edge of the blank against the infolders.

The problem encountered with most of these machines is that different nest plates are often provided for each size of blanks. Although some machines have been provided with means for varying the length of the nest plates without having to replace the full nest plates, such means are not easily adjustable.

It is therefore the main feature of the invention to provide an improved apparatus for forming fabric blanks of various length wherein the nest plate is made of two end portions of fixed dimensions which may be displaced with respect to each other and of an intermediate portion the length of which may be varied depending on the size of the blank. This is particularly useful in the manufacture of collar bands wherein the ends of the collar bands do not vary in shape. The length of the intermediate portion of the blank only needs to be varied to obtain various sizes of bands.

It is also a feature of the invention to provide means for moving the two end portions of the nest plate in synchronism thereby permitting easy adjustment of the nest plate. The intermediate portion of the nest plate is removable and may be changed to suit various sizes of blanks.

It is a further feature of the invention to provide means for easily adjusting the punch assembly for matching the various sizes of nest plates.

The nest plate assembly, in accordance with the invention, comprises a nest plate having two end portions and a removable intermediate portion as mentioned above. The nest plate is supported by a carriage assembly including two supporting structures holding the end portions of the nest plate and means are provided for moving the supporting structures for sliding the two end portions of the nest plate towards or away from each other for positioning an intermediate portion of the nest plate between the end portions thereof.

The carriage assembly includes two shafts secured to the apparatus. One of the shafts is threaded through the above-mentioned supporting structures for permitting movement of the supporting structures upon rotation of the one shaft. Such permits movement of the end portions of the nest plate in synchronism and thus an easy adjustment of such end portions.

The nest plate has a cavity shaped in accordance with the finished blanks and a punch assembly is provided for inserting a somewhat larger blank into the cavity. The punch assembly comprises four punch sections overlapping each other and arranged to form a four corner punch assembly. A head structure including two separate plates is provided for supporting the punch assembly. The plates are movable towards or away from each other and to each one is secured two punch sections thereby permitting to longitudinally slide two punch sections with respect to the other two punch sections to suit the cavity of the nest plates.

The invention will now be disclosed more clearly in the following detailed description, with reference to the accompanying drawings, of a preferred embodiment thereof which, however, is to be taken by way of example only. In the drawings:

FIG. 1 is a perspective view of the machine in accordance with the invention;

FIG. 2 is a partially sectional side view of the machine illustrating the movement of the head structure thereof and some of the elements surrounding the nest plate;

FIG. 3 illustrates a top view of the folder plate carriage assembly and of the nest plate;

FIG. 4 is an exploded view of the head structure of the machine;

FIGS. 5 to 7 illustrate the structure and operation of the collapsible punch assembly;

FIGS. 8 to 12 illustrate the sequential operation of the machine in accordance with the invention; and

FIGS. 13 and 14 illustrate a device for picking up the finished blanks and for delivering them to a tray located at the side of the apparatus.

In FIG. 1 of the drawings, there is illustrated a machine 10 for forming fabric blanks comprising generally a head structure 11 supporting a collapsible punch assembly 12 shown in a lowered position into the cavity of a nest plate 13. A pick-up arm 14 is also shown for delivering the finished fabric blanks to a side tray 15 in a known manner. There is further illustrated in dashed lines a control panel 16 which does not form part of the present invention.

FIG. 2 illustrates, in full lines, the head structure 11 in a retracted position wherein the collapsible punch 12 is raised from the cavity of the nest plate 13. The head structure 11 is supported, as it will be disclosed more fully in a later part of the description, by a bar 17 which is pivotally connected to a piston 18 operated by a cylinder 19. The end of bar 17 which is located opposite the head structure is provided with a roller 20 which is adapted to slide in a slot 21 in a guiding member 22 which is pivotally mounted on the structure of the machine. Upon actuation of piston 18, head structure 11 is moved upwardly from its lowermost position illustrated in dashed lines to the intermediate position illustrated in full lines. During the upward movement of the head structure 11, the roller 20 of bar 17 slides in slot 21 until it reaches the upper end of slot 21. Upon further movement of piston 18, head structure 11 pivots to the inclined uppermost position shown in dashed lines while guiding member 22 rotates slightly clockwise to permit the pivotal movement of head structure 11. Such pivotal movement of head structure 11 is provided for permitting the operator to

more clearly see the nest plate 13 to insert a new fabric blank therein when a previous blank has been formed.

As illustrated in FIG. 3, the nest plate 13 is made in three parts: two identical end portions 13a and a removable intermediate portion 13b which may vary in length for forming blanks of various sizes. The nest plate is supported by a carriage assembly indicated generally by numeral 30 and including two shafts 31 and 32. Shafts 31 and 32 pass through two separate supporting structures 33 (only one shown) holding the end portions 13a of the nest plate as it will be explained later. Shaft 32 is threaded and engages threads of opposite directions in supporting structures 33 for permitting movement of supporting structure 33 on the right hand side of the right hand side of the machine towards the corresponding supporting structure 33 on the left hand side of the machine upon rotation of handle 35 in synchronism.

Upon each supporting structure 33 is secured two elongated members 36 which support the end portions 13a of the nest plate 13 (see also FIG. 2). Movement of the supporting structures thus permits the sliding of the end portions of the nest plate for positioning an intermediate portion 13b in between the end portions 13a. Intermediate portion 13b is shown as being secured to the ends of elongated members 36 but it could be secured directly to the carriage assembly.

A heating element 37 passes through elongated members 36 to heat up the nest plate 13 as required to effect the blank forming operation.

At each end of supporting structure 33 is secured a raising plate 38 (which may not be required) for supporting a folder plate actuator 34. Actuator 34 includes two bushings 39 and 40 secured to plate 38 and a movable block 41 secured to a piston 42. An hydraulic cylinder 43 slides piston 42 and block 41 in bushings 39 and 40. A folder plate 44 is secured to each block 41 and is consequently moved by the actuation of cylinder 43 in a direction such as to move towards or away from each other two diagonally opposite folder plates 44. Such diagonal movement of two opposite folder plates 44 performs the folding operation of the bordering portion of the blank over the back edge of the collapsible punch to form the hem portion of the blank, as mentioned previously.

Folder plates 44, in a manner similar to nest plate 13, comprise an exchangeable intermediate portion 45 which may be of various lengths for making blanks of various dimensions.

As illustrated in FIGS. 2 and 3, a pressure plate 50 having an elongated dovetail portion is located between elongated members 36 and is secured to an elongated bar 51 having an undercut slot 52 matching the dovetail portion of plate 50. The pressure plate 50 is covered by a sheet of Teflon material 53 and is movable upwardly under the action of piston 54 for pressing the blanks as it will be disclosed more fully in the later part of the description.

Pressure plate 50 is also made of two end parts and of an exchangeable center part for making blanks of various lengths. It may be positioned longitudinally by sliding it into slot 52 in elongated bar 51.

Referring now to FIG. 4, the head structure of the machine includes a bar 17, as mentioned previously, to which is secured a plate 60 carrying two end plates 61

which are mounted to plate 60 by means of L-shaped members 63 and 64. Each plate 61 is movable longitudinally on plate 60 by means of a screw 65 which is rotatably mounted on plate 60 and engages a threaded block 66 secured to plate 61. The function of screw 65 will be mentioned later on in the description.

To each plate 61 is secured two pairs of angle members 67 and 68 holding a rod 69 upon which slides a block 70 carrying rollers 70a which bear on plate 61 and prevent tilting of the block 70. The two blocks 70 located on each plate 61 are operated by levers 71 which are pivotally interconnected at one end and pivotally connected at their other ends to the respective blocks 70. A lever 72 is secured at one end to a shaft 73 and pivotally connected at its other end to the interconnected ends of levers 71. Rotation of shaft 73 causes movement of the levers 71 and 72 in such a way as to slide blocks 70 on rods 69.

Shafts 73 are rotated by levers 74 having end rollers 75 which slide into slots 76 of a cross-member 77 when such cross-member is moved in a direction parallel to the longitudinal axis of arm 17 by a cylinder 78.

An under-cut member 79 is secured to each block 70 and supports a dovetail member 80 to which is fastened an angle member 81 supporting the collapsible punch assembly 12 which has been mentioned briefly in the description of FIG. 1 and will be disclosed more fully in a later part of the description.

Referring to FIGS. 5, 6 and 7, it is seen that members 79 move with blocks 70 in a direction making an angle α with the longitudinal axis of member 79 to collapse the punch assembly 12 which is made of sections 82-85 overlapping each other. Each of the sections 82-85 has two upwardly bent portions which are secured to a corresponding downwardly bent portion of angle member 81 also illustrated in FIG. 4. In addition, post members 86 support the ends of sections 83 and 85 to prevent such portions from being bent during operation. It is easily seen that during the movement of blocks 70, two diagonally opposite sections 82-84 and 83-85 of the punch assembly are displaced towards or away from each other.

Although the overall shape of the punch is one of a shirt collar, it is to be understood that other punch configurations are also possible. This also applies to the shape of the nest plate 13.

The screw 65 illustrated in FIG. 4 permits to move plates 61 towards or away from each other and at the same time slide the two portions 83 and 84 of the punch assembly on its other two portions 82 and 85 so as to permit forming of blanks of various lengths. In addition, dovetail member 80 is slidable within under-cut member 79 in such a way as to further vary the amount of longitudinal overlapping of the sections 82 to 85 of the collapsible punch assembly 12 if required.

The operation of the apparatus so far described will be disclosed with reference to FIGS. 8-12. At the beginning of each forming operation, the collapsible punch assembly 12 is fully extended and its dimensions are slightly smaller than the size of the cavity of nest plate 13. An oversize pre-cut fabric blank 87 is positioned over nest plate 13 and collapsible punch assembly 12 is lowered into the cavity of the nest plate 13 to force the oversize blank 87 into the cavity of the nest plate 13 thereby causing the bordering portion of the

oversize blank 87 to fold along the inside walls of the nest plate 13. The folding plates 44 are then operated in the direction indicated in FIG. 10 of the drawings for folding the bordering portion of the blank 87 over the back edge of the collapsible punch to form a hem portion. The punch assembly 12 is then collapsed as indicated in FIG. 11 and pressure plate 50 is moved upwardly to press the hem portion of the blank against the edge of the folder plate 44. Finally, the collapsible punch assembly 12 is raised, the folder plates 44 are withdrawn and the blank 87 is ejected. Such ejection may be done by means of a pin 88 or by any other suitable means.

If after having made a number of blanks of a predetermined size it is desired to make blanks of a different size, the intermediate portion 13b of the nest plate is replaced by different one and the end portions 13a are moved in position by handle 35. The punch assembly is subsequently adjusted by means of screws 65.

Referring to FIGS. 13 and 14, the apparatus in accordance with the invention, may further comprise an arm 14 for picking up the ejected blanks 87 and for carrying them to tray 15 at the side of the apparatus. Arm 14 has a finger 91 fixed at one end thereof and is pivotally mounted at its other end to a bracket 92 secured to the edge of the apparatus. A shaft 93 is secured to such other end of arm 14 and is operated by piston 94 of cylinder 95 through a lever 96 for pivoting the arm 14 through an angle of approximately 90°. Arm 14 has a rotatable shaft (not shown) mounted coaxially therewith and carrying a rotatable finger 97 at one end thereof. The other end of the rotatable shaft is secured to a block 98 carrying a roller 99 which is adapted to engage cams 100 and 101. Cam 100 causes the relative opening of fingers 91 and 97 for picking up the ejected blank 87 at the position illustrated in dashed lines in FIG. 13. Upon rotation of arm 14, roller 99 falls down cam 100 and fingers 91 and 97 are closed for holding blank 87 and for carrying the same to tray 15. When arm 14 reaches the position illustrated in FIG. 14 above tray 15, roller 99 engages cam 101 and causes the relative opening of fingers 91 and 97 for releasing the blank located between the fingers.

It is to be understood that various modifications may

be made to the embodiment disclosed without departing from the scope of the invention described in the following claims. In particular, the means for moving the end portions of the nest plate could be modified in various ways and the invention is intended to cover such modifications. In addition the two screws 65 used for adjusting the punch assembly could be combined in a single one for moving the two plates 61 in synchronism.

We claim:

- 10 1. In an apparatus for forming a fabric blank including a nest plate having a cavity of variable size shaped in accordance with a finished blank, a punch assembly for inserting a somewhat larger blank into said cavity and comprising:
  - a. four punch sections overlapping each other and arranged to form a four corner punch assembly;
  - b. a head structure including two separate plates for supporting said punch assembly;
  - c. means for attaching two punch sections to each one of said plates; and
  - d. screw means secured to said head structure and connected to said plates for sliding the two punch sections attached to one plate towards the two punch sections attached to the other plate to match the length of the punch assembly to the length of the cavity of the nest plate.
- 20 2. A punch assembly as defined in claim 1, including means for collapsing two diagonally opposite sections of said four corner punch assembly towards or away from each other so as to collapse or extend said punch assembly.
- 30 3. A punch assembly as defined in claim 2, wherein said means for moving two diagonally opposite punch sections includes two slide block assemblies mounted underneath each of said plates, each slide block assembly including a slide rod secured to said plates and a block slidably mounted on said rod and holding one of the sections of said four corner punch assembly, and lever means for sliding said blocks simultaneously on said rods towards or away from each other.
- 40 4. A punch assembly as defined in claim 3, further comprising means for lowering and raising said head structure into and away from the cavity of said nest plate.
